[57] CLAIM

The ornamental design for a semi-conductor with conducting pattern, as shown.

DESCRIPTION

FIG. 1 is a top perspective view of a substrate with conducting pattern showing our new design; FIG. 2 is a bottom perspective view thereof; FIG. 3 is a right side elevational view thereof; FIG. 4 is a left side elevational view thereof; FIG. 5 is a rear elevational view thereof; and FIG. 6 is a front elevational view thereof; FIG. 7 is a top plan view thereof; and FIG. 8 is a bottom plan view thereof.

FIG. 1

FIG. 2

FIG. 3

FIG. 4

FIG. 5

FIG. 6

FIG. 7

FIG. 8

UNITED STATES PATENT AND TRADEMARK OFFICE
CERTIFICATE OF CORRECTION

PATENT NO. : Des. 319,045

DATED : August 13, 1991

INVENTOR(S) : Terutomi Hasegawa, et al

It is certified that error appears in the above-identified patent and that said Letters Patent is hereby corrected as shown below:

Under "Claim", after "semi-conductor" insert --substrate--.

Under "Description", Fig. 1, line 1, before "substrate"
insert --semi-conductor--.

Signed and Sealed this

Twenty-second Day of June, 1993

Attest:

MICHAEL K. KIRK

Attesting Officer

Acting Commissioner of Patents and Trademarks
